TIME-DELAY RELAY SYSTEM

Milton W. Griffes and Harold J. Rathbun, Cleveland, Ohio, assignors to The Electric Controller & Manufacturing Company, Cleveland, Ohio, a corporation of Ohio

Application April 25, 1945, Serial No. 590,292

11 Claims. (Cl. 175—320)

1

This invention relates to motor control systems, the illustrative examples hereinafter disclosed being improved control systems for automatically short circuiting the resistance in a circuit of an electric motor during acceleration of the motor and for introducing a time delay between the closing of successive starting switches, the extent of the time delay intervals being dependent upon the rate of energy accumulation of an electrical energy storage device such as a condenser.

Heretofore, in the control of translating devices other than motors by timing circuits, it has been proposed to connect a condenser, an adjustable resistor, and the operating winding of an electromagnetic relay in series with each other across a source of constant unidirectional voltage, the electrical constants of the circuit being so proportioned that, upon initial application of voltage to the circuit terminals, the initial impulse of condenser charging current is sufficient to cause pick-up or actuation of the relay which thereafter remains in its actuated or closed magnetic circuit position until the condenser charging current decreases to the drop-out current value of the relay. A series connected condenser, resistor, and relay winding circuit such as just described and in which all of the relay current passes through the timing condenser is not satisfactory when supplied with constant voltage for measuring the time relay intervals between the closing of successive motor acceleration switches because, when the resistance of the circuit is made low enough to permit the initial flow of charging current to be large enough to pick up the relay, the resistance is too low to delay adequately the charging time of the condenser, and consequently the timing period is too short for many purposes including that of motor starting control. This disadvantage is aggravated by low voltage conditions that often occur on industrial power supply systems. The time delay period can obviously be increased by using a condenser of larger capacity, but this expedient is generally not justified both because of increased cost and because of the larger space required. Other disadvantages of such prior series connected timing circuits are that relatively large variations in the resistance of the resistor have but little effect on the time intervals so that other means must be resorted to in order to obtain the usual required adjustment of the duration of the time interval, and that when two or more timing circuits are used to control two or more acceleration switches, difficulty is encountered in arranging the circuits

so that all possibilities of incorrect switching sequence are obviated.

By taking advantage of the phenomenon that considerably less current is required to hold a relay in its actuated position than is required to actuate it, various modifications of the foregoing type of series connected condenser timing circuit have heretofore been proposed for increasing the timing interval for unit of capacity. 10 However, the switching sequences required in the prior modified timing circuits are such that the circuits are not suitable for controlling motor acceleration and in some instances also require the use of a relay having either a tapped operating winding or two separate windings.

The present invention involves timing circuits of the above indicated character and takes advantage of the fact that the drop-out current of a relay is less than the relay pick-up current, 20 but the timing circuits are so arranged as to be eminently suitable for controlling motor acceleration and each of the timing relays requires but a single, untapped operating winding. More specifically, in accordance with this invention, 25 circuit means are provided for temporarily bypassing the condenser and resistor portion of a series connected condenser, resistor, and relay winding timing circuit so as to supply, upon initial application of voltage to the circuit, sufficient current to the relay winding to pick up the relay, the by-pass circuit means subsequently becoming inoperative due to closure of a motor starting switch or charging of a second condenser. After the by-pass circuit means becomes inoperative, the relay is held in its actuated position 30 for a time interval by the charging current flowing through the timing condenser thereby to delay operation of a second motor starting switch. The by-pass circuit preferably conducts by itself 35 sufficient current to pick up the relay, the circuit including the timing condenser either conducting substantially none or a very small percentage of the relay current during the time that the by-pass circuit is operative.

40 The improved series connected condenser and relay timing circuit disclosed herein not only provides a timing interval of longer duration for a given size of condenser than heretofore obtainable with a circuit not provided with a by-pass circuit means so that the improved circuit is 45 useable for the control of motor acceleration, but also greatly increases the range of adjustment of the timing interval and makes possible the use of simplified control connections for both 50 single and multiple step motor starters which

insure the proper sequence of operation and eliminate all close contact races.

For further increasing the time delay interval for microfarad of capacity in the circuit, an additional relay current path is provided in an alternative embodiment of the invention to permit a small amount of relay current, which is less than the drop-out current value of the relay, to flow around both the temporary by-pass circuit and the series connected condenser and resistor circuit throughout the timing interval. The additional current path for supplying current to the relay winding permits the relay to remain in its operated position until the charging current flowing through the condenser decreases to a value which is less than the difference between the current flowing through the additional current path and the drop-out current value of the relay.

An important object of this invention is to provide a motor control system having the foregoing advantages and features.

Another object is to provide an improved time delay control system especially adapted for motor control.

Another object is to provide an improved time delay control system in which an electromagnetic relay is temporarily held in its actuated or energized position by the charging current of a condenser connected in series with the operating winding of the relay.

A further object is to provide a time delay control system in which a relay is temporarily held in its actuated position by the charging current of a condenser connected in series with a resistor and the relay winding and in which a circuit temporarily by-passing the condenser and resistor supplies substantially all of the current for initially actuating the relay.

An additional object is to provide an improved control system for an electric motor which includes means responsive to the charging current of a condenser for controlling the operation of electromagnetic switches.

Other objects include the provision of a plurality of co-operating time delay circuits of the character indicated above in which the time intervals are individually adjustable, the provision of a plurality of such circuits arranged for controlling acceleration switches for an electric motor, the provision of a plurality of such circuits in which the starting of the timing interval of one of the circuits is dependent upon the completion of the timing interval of another of the circuits, and the provision of a plurality of such circuits in which simplified connections are used for obtaining the proper sequence of operation.

A still further object is to provide a motor control system in which a relay, having normally-closed contacts in series with the operating winding of a switch to be operated after a time delay, is operated to the open position of its contacts before a circuit to the switch can be completed and then is held in its operated position for a time interval measured by the charging time of a condenser.

Other objects and advantages will become apparent from the following description wherein reference is made to the drawings, in which:

Fig. 1 is a circuit diagram embodying the invention;

Fig. 2 is a circuit diagram of a modification;

Fig. 3 illustrates a further modification;

Fig. 4 is a graph illustrating time-resistance

characteristics of a prior art time delay circuit, and

Fig. 5 is a graph illustrating time-resistance characteristics obtainable with the time delay circuit of Figs. 1 and 2.

Referring to Fig. 1, a direct current motor 10 having an armature winding 10a and a series field winding 10b is arranged to be connected between a pair of supply conductors 11 and 12 through series connected accelerating resistors 14 and 15 when normally open main circuit contacts 16a of an electromagnetic contactor or switch 16 are in their closed position. The switch 16 additionally has normally closed auxiliary contacts 16b, normally open auxiliary contacts 16c and 16d, and an operating winding 16w the energization of which is controlled by a pilot device or master switch shown as a push button 18 having normally open contacts 18a and normally closed contacts 18b. The accelerating resistors 14 and 15 are arranged to be short circuited upon closure of normally open main circuit contacts 19a and 20a, respectively, of electromagnetic contactors or switches 19 and 20, respectively. The switch 19 is additionally provided with a pair of normally closed auxiliary contacts 19b and 19c, a pair of normally open auxiliary contacts 19d and 19e, and an operating winding 19w. The switch 20 is additionally provided with normally closed auxiliary contacts 20b, normally open auxiliary contacts 20c, and an operating winding 20w. The energization of the windings 19w and 20w is controlled respectively, in a manner to be described, by normally closed contacts 21a of an electromagnetic relay 21 and normally closed contacts 22a of an electromagnetic relay 22. The relays 21 and 22 have operating windings 21w and 22w, respectively, and are preferably designed, as by having moving parts which are relatively smaller than the moving parts of the switches 16, 18 and 20, so that they respond more quickly upon energization of their respective windings than do the switches. That is, when the winding of a switch 45 and the winding of a relay are energized concurrently, the relay moves to its operated or actuated position before the switch. Any suitable type of relay may be used for the relays 21 and 22 so long as it has a drop-out current value 50 which is less than its pick-up current value, but preferably the relays 21 and 22 are of the clapper type having either a fixed drop-out current value or having means for adjusting the drop-out current value, it being understood that the representation of the switches and relays in the drawings is merely schematic.

For controlling time delayed drop-out of the relay 21, a condenser 24 and an adjustable resistor 25 are connected in series with each other 60 and with the winding 21w between the conductor 12 and a conductor 11a which is electrically connected to the conductor 11 when the contacts 16c and/or 18a are closed. Time delayed drop-out of the relay 22 is controlled by a condenser 28 and an adjustable resistor 29 connected in series with each other and with the winding 22w between the conductors 11a and 12. A by-pass circuit around the condenser 24 and the resistor 25 extends through the contacts 16b, and a similar by-pass circuit around the condenser 28 and the resistor 29 extends through the contacts 19b. Preferably in Fig. 1, the by-pass circuits are of relatively low resistance and, as shown, constitute short circuits of the respective series connected condensers and resistors. Other details

of the control system of Fig. 1 will become apparent from the following description of operation.

With the conductors 11 and 12 connected to a suitable source of unidirectional voltage, closure of the contacts 18a of the push button 18 connects the winding 16w for energization across the conductors 11 and 12 through a conductor 30. In response to the energization of its winding 16w, the switch 16 operates to close its contacts 16a to connect the motor 10 to the source of power in series with the accelerating resistors 14 and 15. Concurrently with completion of the energizing circuit for the winding 16w, closure of the contacts 18a also completes an energizing circuit for the winding 21w from the conductor 11 through conductors 31 and 11a, the still closed contacts 16b in the by-pass circuit, a conductor 34, the winding 21w, a conductor 35, and the normally closed contacts 19c to the conductor 12. Upon energization of its winding 21w, the relay 21 moves to its actuated position and opens its contacts 21a, the contacts 16b subsequently opening after a predetermined short interval of time to interrupt the by-pass circuit. Having been moved to a closed position of its magnetic circuit by the relatively large current flowing through the by-pass circuit, the relay 21 is held temporarily in its actuated or energized position after the opening of the contacts 16b by the relatively smaller and gradually decrescent charging current which starts to flow through the condenser 24 and the resistor 25 as soon as the contacts 16b open. The rate of decline in the charging current of the condenser 24 is determined by its microfarad capacity, the applied voltage and the ohmic resistance of the resistor 25 and the winding 21w. Closure of the contacts 16c completes a circuit around the contacts 18a from the conductor 11 to the conductor 11a so that the contacts 18a may be opened at this time without operative effect, and closure of the contacts 16d has no immediate effect because by the time the contacts 16d have closed the contacts 21a in series therewith and with the winding 19w have opened. It should be noted that the relay 21 need respond but a very short time before the switch 16 operates to open the contacts 16b, since even if the contacts 21a and 16d move concurrently, no circuit therethrough is completed.

Connection of the conductor 11 to the conductor 11a also completes an energizing circuit for the winding 22w through a conductor 36, the contacts 19b, a conductor 38, the winding 22w, the contacts 20b, and a conductor 39 to the conductor 12. Operation of the relay 22 to its energized position consequent upon energization of the winding 22w has no effect at this time since the contacts 22a are in series with the still open contacts 19e.

When the charging current flowing through the condenser 24 had decreased to the drop-out current value of the relay 21, the relay 21 drops out, i. e. returns to its normal position, and the contacts 21a reclose to complete an energizing circuit for the winding 19w from the conductor 11a through the now closed contacts 16d, the contacts 21a, and the winding 19w to the conductor 12. Operation of the contactor 19 consequent upon the energization of its winding 19w closes the contacts 19a, 19d, and 19e and opens the contacts 19b and 19c. Closure of the contacts 19a short circuits the resistor 14 thereby increasing the voltage impressed on the motor

10. Closure of the contacts 19d completes a discharge circuit for the condenser 24 through a portion of the resistor 25, the contacts 19d, and a conductor 40 to the conductor 11a, and opening of the contacts 19c prevents any possible operation of the relay 21 as a result of the closure of the contacts 19d.

Closure of the contacts 19e has no effect at this time because the contacts 22a in series therewith are open, but opening of the contacts 19b interrupts the by-pass circuit around the condenser 28 which thereupon starts to draw a charging current which temporarily holds the relay 22 in its energized position. The path of the charging current for the condenser 28 is from the conductor 11a through the condenser 28, the resistor 29, the winding 22w, the contacts 20b, and the conductor 39 to the conductor 12. After the expiration of a time interval determined by the applied voltage, the capacity of the condenser 28, and the combined resistance of the resistor 29 and the winding 22w, the charging current of the condenser 28 decreases to the drop-out current value of the relay 22 which thereupon returns to its normal position in which the contacts 22a are closed. Closure of the contacts 22a completes an energizing circuit for the winding 20w from the conductor 11a through the contacts 22a, the winding 20w, and the now closed contacts 19e to the conductor 12. The switch 20 in response to the energization of its winding 20w closes its contacts 20a to short circuit the resistor 15, closes its contacts 20c to complete a discharge circuit for the condenser 28 through a small portion of the resistor 29, the contacts 20c, and the conductor 40 to the conductor 11a, and opens its contacts 20b to prevent any possible operation of the relay 22 as a result of the closure of the contacts 20c.

Short circuiting of the resistor 15 connects the motor directly across the conductors 11 and 12, the time delay provided by the circuits including the condensers 24 and 28 having delayed the successive operation of the switches 16, 19 and 20 so as to effect proper acceleration of the motor 10. It should be noted that the circuit of Fig. 1 is so arranged that the windings 16w and 21w are both energized before the circuit to the winding 19w can be completed, and that so long as the contacts 21a open before the contacts 16d close there can be no false operation of the switches due to a "contact race."

The motor 10 may be stopped at any time by opening the contacts 18b to interrupt the energizing circuit for the winding 16w which permits the switch 16 to return to its normal position wherein the contacts 16a are open. The switches 19 and 20 return to their normal position upon drop-out of the switch 16 because the circuit to their energizing windings is interrupted at the contacts 16c, the contacts 18a having previously been opened. Since the condensers 24 and 28 are almost instantly discharged upon pick-up of the switches 19 and 20, respectively, immediate pick-up of the switch 16 after drop-out thereof does not prevent the full acceleration time intervals from occurring. If the motor 10 for any reason does not slow down rapidly, the relatively low resistance discharge circuits for the condensers 24 and 28 through the contacts 19d and 20c may be dispensed with since reclosure of the contacts 16b completes a discharge circuit for the condenser 24 and reclosure of the contacts 19b completes a discharge circuit for the condenser 28. These latter circuits are of

relatively high resistance so that a longer time is required for complete discharge of the respective condensers. So long as the duration of the discharge interval of the condenser 24 is less than the deceleration time of the motor 10, the motor will be properly re-accelerated since, if the motor has not stopped, its countervoltage will limit the motor current peaks during re-acceleration so that the shortened time delay interval resulting because the condenser 24 has not been fully discharged will be of no material consequence.

In Fig. 4 which illustrates the operation of a condenser timing circuit merely having a condenser, a resistor, and a relay winding connected in series and without the by-pass circuit for initially supplying substantially all of the current required to pick up the relay, the time during which the relay is picked up is plotted against the ohmic value of the series connected resistor. A curve 41 is the time-resistance characteristics of such a circuit having a condenser of a given capacity C , and curves 42 and 43 are time-resistance characteristics for circuits having a condenser of capacity two times C and four times C , respectively. It will be noted that as the size of the condenser is increased, increased periods of time delay are obtained, and that by increasing the ohmic value R of the series connected resistor, only slight increases in time delay are obtained. In order to prolong the flow of charging current it is desirable to increase as much as possible the ohmic value R of the series resistor, but if, as in the type of circuit being considered, the initial impulse of condenser charging current alone is used to pick up the relay, there is a limit beyond which it is impossible to increase the resistance of the circuit. This limit for a rated value of supply voltage and for a given relay is represented by a curve 45 in Fig. 4, and it is obvious that if the supply voltage is decreased, the limiting resistance curve 45 moves to the left in Fig. 4.

Referring now to Fig. 5, which illustrates the time-resistance characteristics of the time delay circuit of Fig. 1, the time scale is the same as that of Fig. 4, but the resistance scale represents an ohmic value ten times as large, hence the indication of the abscissa point ten times R . The same relay and relay winding were used in obtaining the data for Figs. 4 and 5, and in Fig. 5 curves 46, 47, and 48 are plotted for the same values of capacity as the curves 41, 42, and 43, respectively, of Fig. 4. Due to the fact that in accordance with this invention the pick-up current of the relay flows through a circuit of low resistance which temporarily by-passes the condenser charging circuit, there is no limiting value of series resistance, such as indicated by the curve 45 of Fig. 4, and, as is apparent from the steepness of the curves 46, 47, and 48 of Fig. 5 as compared with the corresponding curves 41, 42, and 43 of Fig. 4, much greater changes in time delay period can be obtained by simply adjusting the value of the series resistor.

In the form of the invention illustrated in Fig. 2, the normally closed contacts 16b of the switch 16 of Fig. 1 are replaced by a condenser 50 and a resistor 51 which are connected in series with each other and in parallel with the condenser 24 and the resistor 25 between the conductors 11a and 34. Similarly the normally closed contacts 19b of the switch 19 of Fig. 1 are replaced by a condenser 52 and a resistor 54 which are connected in series with each other and in parallel

with the condenser 28 and the resistor 29 between a conductor 11b and the conductor 38. The conductor 11b is connected to the conductor 11a when the contacts 19e of the switch 19 are closed. The capacity of each of the condensers 50 and 52 may be, and preferably is, considerably less than the capacity of either of the condensers 24 and 28. The resistors 51 and 54 serve only to limit the inrush current of their respective relay windings and may be omitted if the resistance of the windings 21w and 22w is sufficient for this purpose. Other differences between the control system of Fig. 2 and that of Fig. 1 are pointed out in the following description of operation of the system of Fig. 2.

With power available at the conductors 11 and 12, closure of the contacts 18a causes operation of the switch 16 and permits an impulse of charging current to flow from the conductor 11, through the conductors 31 and 11a, the condenser 50, the resistor 51, and the operating winding 21w to the conductor 35 which is sufficient to cause the relay 21 to operate and open its contacts 21a. After a relatively short interval of time, the condenser 50 becomes fully charged and current no longer flows therethrough to the winding 21w, but the relay 21 is temporarily held in its picked-up position by the charging current flowing through the condenser 24 and the resistor 25. Consequent upon the accumulation of sufficient charge on the condenser 24 to cause the current flowing therethrough and through the resistor 25 to the winding 21w to be reduced below the drop-out current value of the relay 21, the relay 21 returns to its normal position and the contacts 21a reclose to effect energization of the winding 19w as described in connection with Fig. 1. Operation of the switch 19, due to energization of its winding 19w, causes closure of the contacts 19a, 19d, and 19e and opening of the contacts 19c. Closure of the contacts 19a causes an increase in the voltage applied to the motor 10, closure of the contacts 19d and opening of the contacts 19c completes a discharge circuit for the condensers 24 and 50, and closure of the contacts 19e completes the circuit from the conductor 11a to a conductor 11b.

Upon energization of the conductor 11b, an impulse of current flows through the condenser 52, the resistor 54, the conductor 38, the winding 22w, the contacts 20b, and the conductor 39 to the conductor 12 which is sufficient to cause the relay 22 to move to the open position of its contacts 22a. The contacts 22a of the relay 22 open before the switch 20 can operate due to the temporary but ineffective energization of its windings 20w which occurred at the instant of closure of the contacts 19e. After the condenser 52 is charged, the by-pass circuit therethrough is, in operative effect, interrupted, and the relay 22 remains in its picked-up position due to current which flows through the condenser 28 and the resistor 29. After the accumulation of a predetermined charge on the condenser 28, the current flowing therethrough to the winding 22w decreases below the drop-out current value of the relay 22 which thereupon recloses its contacts 22a to complete the energizing circuit for the winding 23w from the conductor 11b to the conductor 12. Operation of the switch 20 consequent upon the energization of its winding 20w causes closure of the contacts 20a which short circuit the remaining acceleration resistance section 15, and causes closure of the contacts 20c and opening of

the contacts 20b which complete a discharge circuit for the condenser 28 and 52.

The time-resistance characteristic curves of Fig. 5 are also illustrative of the operation of the timing circuit of Fig. 2 because, since the resistors 51 and 54 have a low resistance and the condensers 50 and 52 have a small capacity, the condensers 50 and 52 become fully charged almost instantly and have very little effect on the respective time periods controlled by the condensers 24 and 28.

In Fig. 3 a portion of one of the previously described timing circuits has been reproduced, and a resistor 55 is shown as added thereto. The resistor 55, which is shown as connected in parallel with the contacts 16b and in parallel with the condenser 24 and the resistor 25, has an ohmic value such that when the contacts 16b are opened and the condenser 24 is substantially fully charged, insufficient current flows therethrough to hold the relay 21 in its picked-up position. The shunt circuit including the resistor 55 supplies current to the relay winding 21w which is in addition to that supplied through the condenser 24 so that the condenser 24 becomes more fully charged before the total current flowing through the winding 21w decreases to the drop-out current value of the relay 21. The time delay period that is obtainable by using the circuit with the resistor 55 is longer for a given size of condenser than that obtainable by using the circuits of Figs. 1 and 2. It is readily apparent that if desired a resistor 55 may be added in a similar manner to one or both of the timing circuits illustrated in Fig. 2.

We claim:

1. In a motor controller, a resistor of relatively high resistance, a timing condenser of relatively large capacity, an electromagnetic switch having an operating winding, connections forming a series circuit including said resistor, condenser, and winding, a by-pass circuit of relatively low resistance connected in parallel with said series connected resistor and condenser and in series with said winding, switch means operable to connect said series circuit across a source of unidirectional voltage, a control condenser of relatively small capacity interposed in said by-pass circuit and chargeable within a predetermined time after operation of said switch means and while said timing condenser is substantially uncharged to prevent the flow of current in said by-pass circuit, and the electrical constants of said circuits being related to each other and to the voltage of said source to permit sufficient current to flow in said circuits to pick up said electromagnetic switch when said switch means is operated and before said control condenser becomes charged.

2. In a motor controller, a resistor of relatively high resistance, a condenser, an electromagnetic switch having an operating winding, means for connecting said resistor, condenser, and winding in series with each other to form a series circuit, switch means operable to connect said series circuit across a source of unidirectional voltage, the electrical constants of said electromagnetic switch and said resistor being so related to each other and the voltage of said source that insufficient current flows through said series circuit to operate said electromagnetic switch upon connection of said series circuit across said source when said condenser is substantially uncharged, a by-pass circuit of relatively low resistance connected in parallel with said condenser and resistor and

in series with said winding, the electrical constants of said by-pass circuit, said resistor, and said electromagnetic switch being so related to each other and to the voltage of said source that the by-pass circuit is operative to prevent material charging of said condenser and that said circuits are operative while said condenser is substantially uncharged to allow sufficient current to flow through said winding to operate said electromagnetic switch, by-pass circuit interrupting means interposed in said by-pass circuit and rendered operative consequent upon and after operation of said switch means and while said condenser is substantially uncharged to prevent current from flowing through said by-pass circuit, and the electrical constants of said electromagnetic switch, said condenser, and said resistor being so related to each other and to the voltage of said source that the condenser charging current that flows upon cessation of current flow through said by-pass circuit is sufficient to hold said electromagnetic switch in operated position for a time interval.

3. In a motor controller, a resistor of relatively high resistance, a condenser, an electromagnetic switch having an operating winding, means for connecting said resistor, condenser, and winding in series with each other to form a series circuit, switch means operable to connect said series circuit across a source of unidirectional voltage, the electrical constants of said electromagnetic switch and said resistor being so related to each other and to the voltage of said source that insufficient current flows through said series circuit to operate said electromagnetic switch upon connection of said series circuit across said source when said condenser is substantially uncharged, a by-pass circuit of relatively low resistance connected in parallel with said resistor and in series with said winding, the electrical constants of said by-pass circuit and said electromagnetic switch being so related to each other and to the voltage of said source that said by-pass circuit is operative while said condenser is substantially uncharged to allow sufficient current to flow through said winding to operate said electromagnetic switch, by-pass circuit interrupting means interposed in said by-pass circuit and rendered operative consequent upon and after operation of said switch means and while said condenser is substantially uncharged to prevent current from flowing through said by-pass circuit, and the electrical constants of said electromagnetic switch, said condenser, and said resistor being so related to each other and to the voltage of said source that the condenser charging current that flows upon cessation of current flow through said by-pass circuit is sufficient to hold said electromagnetic switch in operated position for a time interval.

4. In a motor controller, a timing control system for delaying the sequential operation of a switch means and a contactor, said system comprising a resistor, a condenser, an electromagnetic relay having an operating winding and normally-closed contacts, a series circuit in which said condenser and resistor are connected in series with each other and with said winding, a by-pass circuit connected in parallel with said series connected condenser and resistor and in series with said winding, a switch means, an electromagnetic contactor having a winding, a contactor operating circuit connecting said normally-closed contacts and said contactor winding in series, means operatively connecting said switch means to said contactor operating circuit

and said series circuit so that upon closure of said switch means said contactor operating circuit, said series circuit, and said by-pass circuit are connected across a source of unidirectional voltage whereby said circuits are initially energized, said by-pass circuit including means rendered operative consequent upon and after operation of said switch means for interrupting current flow in said by-pass circuit, said by-pass circuit being of such low resistance that said condenser does not accumulate an appreciable charge while said by-pass circuit is conducting current, energization of said series circuit and said by-pass circuit causing pick-up of said relay before, and permitting charging of said condenser after, said by-pass circuit ceases to conduct current, and pick-up of said relay opening said normally-closed contacts before said contactor is operated as a result of current flowing in its operating winding, whereby said contactor does not operate until its winding is energized after drop-out of said relay resulting from the charging of said condenser.

5. A timing control system comprising an electromagnetic switch and a pair of electromagnetic contactors, electromagnetic relays having normally-closed contacts in energizing circuits respectively for said contactors respectively, operating windings for said relays respectively, series connected condenser and resistor combinations connected in series with said windings respectively, by-pass circuits connected in parallel with said series connected condenser and resistor combinations respectively and in series with said relay windings respectively, means for energizing said electromagnetic switch and operable concurrently to energize said relay windings through said by-pass circuits respectively, means rendered operative consequent upon energization of said electromagnetic switch to interrupt one of said by-pass circuits thereby causing a charging current to start to flow through one of the condensers and the winding associated therewith, diminution of the charging current as said one of said condensers charges causing drop-out of one of said relays thereby to cause said contacts of said one relay to close to complete the energizing circuit of one of said contactors, means rendered operative consequent on operation of said one of said contactors to interrupt said other by-pass circuit thereby causing a charging current to start to flow through the other of said condensers and the winding associated therewith, diminution of the charging current as said other condenser charges causing drop-out of the other relay thereby to cause said contacts of said other relay to complete the energizing circuit of the other of said contactors.

6. In a motor controller, a resistor of relatively high resistance, a condenser, an electromagnetic relay having an operating winding, a series circuit in which said condenser and said resistor are connected in series with each other and with said winding, a by-pass circuit of relatively low resistance connected in parallel with said series connected condenser and resistor and in series with said winding, a switch means, means operatively connecting said switch means to said series circuit so that upon closure of said switch means said series circuit and said by-pass circuit can become connected across a source of unidirectional voltage whereby said circuits can be initially energized concurrently, by-pass circuit interrupting means interposed in said by-pass circuit and rendered operative consequent

upon operation of said switch means for preventing the flow of current in said by-pass circuit, said by-pass circuit interrupting means including means operative to impart a time delay period between the operation of said switch means and the operation of said by-pass circuit interrupting means, and the electrical constants of said circuits and said relay being so related to each other and to the voltage of said source that said condenser does not accumulate an appreciable charge while said by-pass circuit is conducting current, that energization of said series circuit and said by-pass circuit causes pick-up of said relay during said time delay period, and that the charging current of said condenser that flows after said by-pass circuit interrupting means operates is sufficient to hold said relay closed for a time interval.

7. A motor controller in accordance with claim 6 characterized in that said by-pass circuit interrupting means comprises normally closed switch contacts interposed in said by-pass circuit and means responsive to operation of said switch means are arranged to open said switch contacts to interrupt said by-pass circuit.

8. A motor controller in accordance with claim 7 characterized in that said switch means comprises a momentary contact push button which upon closure can connect said series circuit and said by-pass circuit across said source and an electromagnetic contactor having an operating winding arranged to be energized from said source upon momentary closure of said push button, said contactor including normally open holding circuit contacts which close upon energization of said operating winding to complete a holding circuit around the contacts of said push button, said switch contacts, and means to effect opening of said switch contacts upon said energization of said operating winding.

9. A motor controller in accordance with claim 6 characterized in that a shunting resistor is connected in parallel with said by-pass circuit and in series with said winding and has an ohmic value so related to the voltage of said source and the drop-out current value of said relay that the additional current that can be supplied through said shunting resistor to said winding during the charging period of said condenser is less than the drop-out current value of said relay.

10. In a motor controller, a resistor, a timing condenser, an electromagnetic switch having an operating winding, means for connecting said resistor, condenser, and winding in series with each other to form a series circuit, switch means operable to connect said series circuit across a source of unidirectional voltage, the electrical constants of said electromagnetic switch and said resistor being so related to each other and to the voltage of said source that insufficient current flows through said series circuit to operate said electromagnetic switch upon connection of said series circuit across said source when said condenser is substantially discharged, a normally completed by-pass circuit connected in parallel with said condenser and resistor and in series with said winding, the electrical constants of said by-pass circuit and said electromagnetic switch being so related to each other and to the voltage of said source that upon connection of said series circuit across said source said by-pass circuit is operative to prevent operative charging of said condenser and is operative while said condenser is substantially uncharged to allow

sufficient current to flow through said winding to operate said electromagnetic switch, by-pass circuit interrupting means interposed in said by-pass circuit and rendered operative consequent upon and after operation of said switch means to prevent current from flowing through said by-pass circuit, and the electrical constants of said electromagnetic switch and said resistor being so related to each other and to the voltage of said source that the condenser charging current that flows upon cessation of current flow through said by-pass circuit is sufficient to hold said electromagnetic switch in operated position.

11. The motor controller of claim 10 characterized in that said timing condenser is of relatively large capacity, said by-pass circuit interrupting means is a condenser of relatively small capacity, and the resistance of said by-pass circuit is materially less than the resistance of said series circuit, whereby after operation of said switch means said condenser in said by-pass cir-

cuit becomes fully charged before said timing condenser.
